Primary Examiner — Llorellys Martinez-Rivera(74) *Attorney, Agent, or Firm* — Stinson LLP(57) **CLAIM**

The ornamental design for a landscape edging as shown and described.

DESCRIPTION

FIG. 1 is a front perspective view of a first embodiment of a landscape edging showing my new design;
 FIG. 2 is a front view thereof;
 FIG. 3 is a top view thereof;
 FIG. 4 is a right side view thereof;
 FIG. 5 is a left side view thereof;
 FIG. 6 is a rear perspective view of a second embodiment of the landscape edging;
 FIG. 7 is a rear view thereof;
 FIG. 8 is a top view thereof;
 FIG. 9 is a left side view thereof; and,
 FIG. 10 is a right side view thereof.

The dash-dash broken lines in the drawings represent portions of the landscape edging and form no part of the claimed design.

The dot-dash broken lines represent a boundary of the claim and form no part of the claimed design.
